UNITED STATES PATENT OFFICE.

WALTER J. BEATTIE, OF COHOES, NEW YORK.

FOLD-COLLAR.

1,191,491.

Specification of Letters Patent. Patented July 18, 1916.

Application filed March 6, 1916. Serial No. 82,313.

To all whom it may concern:

Be it known that I, WALTER J. BEATTIE, a citizen of the United States, residing at Cohoes, county of Albany, and State of New York, have invented certain new and useful Improvements in Fold-Collars, of which the following is a specification.

Reference may be had to the accompanying drawings, and the reference characters 10 marked thereon, which form a part of this specification. Similar characters refer to similar parts in the several figures therein.

In the fold-collars of the kind to which this invention relates, the folded-over top of 15 the collar tends to press against the back collar-button and force the same with uncomfortable pressure against the back of the neck of the wearer.

The principal object of the invention is to 20 relieve such pressure of the folded-over top upon the back collar-button while preserving the appearance, and contour of the lower edge, of the top.

Figure 1 of the drawings is a rear view in 25 perspective of a fold-collar embodying my invention. Fig. 2 is a horizontal section of the back part of the same on the broken line 2—2 in Fig. 1. Fig. 3 is a rear view of a broken-away back-portion of the collar before the patch is inserted in the notched portion of the folded-over top. Fig. 4 is a 30 plan view of the patch previous to its application to the top. Fig. 5 is a vertical section of the patch on the broken line 5—5 in Fig. 4.

Referring to the drawings wherein the invention is shown in preferred form, 1 is the band and 2 is the folded-over top of a fold-collar, both being made of a plurality of 40 plies of fabric as usual. The band is provided with the usual back button-hole, 3, for the back collar-button, 4, whereby the band is attached to the neckband, 5, of a shirt. In the vicinity of the back button-hole in the band, the top is formed with a 45 notch or cut-out, 6, in its lower edge, whereby the top is prevented from pressing against the collar-button inserted in said back button-hole, 3. Such a notched or cut-out top has been employed with satisfactory 50 results so far as relieving the uncomfortable pressure upon the neck of the wearer is concerned; but its popularity has been limited for the reason that fastidious persons hesitate to wear a collar which exposes the back 55

collar-button or the band of the necktie at the back, as does a collar having the top so notched.

In carrying out my invention, I employ a patch, 7, to bridge over the notch, 6, and 60 complete the contour of the lower edge of the folded-over top. The patch is preferably made of a piece of fabric doubled upon itself to form a folded edge, 8, which completes the contour of the lower edge of 65 the top, and is preferably attached to the top by inserting its raw edges between the plies of the top and inserting a line of stitching, 9, through the inturned edges of the plies of the top and the inserted portion of 70 the patch along the edge of the notch. The patch is preferably made substantially wider than the notch and is fulled as inserted so that its fullness adapts it to bulge outwardly beyond the normal surface-lines of the top 75 as shown in Fig. 2, so as to not press upon the back collar-button in use.

When the collar has been starched and ironed, the joint between the patch and edges of the notch will be inconspicuous and 80 the collar seen from the rear will appear little different from any ordinary fold-collar, as the contour of the lower edge of the top will be continuous and the band of the necktie and the back collar-button will be fully 85 concealed.

What I claim as new and desire to secure by Letters Patent is—

1. A fold-collar having a band provided with a back buttonhole, and a folded-over 90 top formed with a notch in its lower edge opposite the back buttonhole in the band, and a fulled patch attached to the top bridging said notch and completing the contour of the lower edge of the top. 95

2. A fold-collar having a band provided with a back buttonhole, and a folded-over top formed of a plurality of plies with a notch in its lower edge opposite the back buttonhole in the band, and a patch inserted 100 and secured between the plies of the top bridging said notch and completing the contour of the lower edge of the top, said patch having a fullness whereby it is adapted to bulge outwardly beyond the normal surface-lines of the top. 105

In testimony whereof, I have hereunto set my hand this 3rd day of March, 1916.

WALTER J. BEATTIE.
